UNITED STATES PATENT OFFICE.

WILLIAM TAKUMA SETO, OF NEW YORK, N. Y.

DESIGN FOR A DECK OF CARDS.

Application filed December 29, 1925. Serial No. 15,896. Term of patent 7 years.

To all whom it may concern:

Be it known that I, WILLIAM TAKUMA SETO, a subject of the Emperor of Japan, and a resident of the city of New York, borough of Manhattan, in the county and State of New York, have invented a new, original, and ornamental Design for Decks of Cards, of which the following is a specification, reference being had to the accompanying drawing, forming part thereof.

Figures 1, 2, 3 and 4 are perspective views which together illustrate a deck of cards showing my new design.

I claim:

The ornamental design for a deck of cards, as shown.

WILLIAM TAKUMA SETO.
